UNITED STATES PATENT OFFICE.

ARTHUR F. POOLE, OF CHICAGO, ILLINOIS, ASSIGNOR TO WAHL ADDING MACHINE CO., OF WILMINGTON, DELAWARE, A CORPORATION OF DELAWARE.

ALGEBRAIC TOTALIZER.

1,202,763.

Specification of Letters Patent.

Patented Oct. 24, 1916.

Application filed January 16, 1914, Serial No. 812,546. Renewed March 22, 1916. Serial No. 85,987.

To all whom it may concern:

Be it known that I, ARTHUR F. POOLE, a citizen of the United States, residing at Chicago, in the county of Cook and State of Illinois, have invented certain new and useful Improvements in Algebraic Totalizers, of which the following is a specification.

My invention is an improvement in algebraic totalizers for use in connection with calculating machines, and is in the nature of an improvement or addition to the algebraic totalizer described in my copending application for calculating machines, Serial

15 Number 751,082, filed February 27th, 1913.

One of the objects of my invention is the provision of an algebraic totalizer with but a single set of carrying mechanism from which totalizer the accurate totals of a series

20 of items, whether said items or totals be positive or negative or both, may be read.

Another object of my invention is the provision of an algebraic totalizer requiring a manual operation when the totalizer

25 passes through zero, and having means for automatically screening the exhibited total in case said total be not the correct total to be read from the machine.

In my application above referred to, I have shown an algebraic totalizer having two sets of number wheels paired 9-0, and a shutter device for indicating which set of numerals shall be read. It is well known in the theory of these totalizers that when

35 the totalizer passes through zero, there is required the addition of a unit in the lowest place in order to correct the total. In

my cited application, I have so connected mechanism to the shutter device that coincident with the shifting of the shutters to

40 designate either the positive or the negative

total, one unit is added into the lowest place of the totalizer thereby correcting the exhibited total.

45 With the device of my cited application one number is always exhibited by the totalizer. It may be that the exhibited number is not the correct total but the complement thereof, which fact the operator de-

50 termines by noticing whether a 9 or a 0 is exhibited in the highest place of the totalizer. This necessity for a mental deter-

mination on the part of the operator when to shift the shutters thereby changing from

55 a positive to a negative total may some-

times result in an error of the operator's failing to notice the figure in the highest decimal place and copying, not the total, but the complement thereof.

It is one of the objects of my present invention to provide automatic means for concealing a wrong total, thereby making the totalizer such that it will exhibit the correct total, or exhibit no total at all. To this end, I have, in addition to the manually operated shutters shown in my cited co-pending application, provided a pair of auxiliary shutters which are connected to and move with the highest number wheel. These auxiliary shutters coöperate with the manual ones in the following way: Assume a positive total in the totalizer of my cited application. The manual shutters are then in a position to exhibit the positive number wheels and conceal the negative ones. Now assume a number greater than the exhibited positive total be subtracted from the totalizer. The highest wheel of the set of exhibited positive numbers will now show a 9, thus indicating that a negative total is to be read. In the operation of the totalizer described in my cited application, the operator noticing that a 9 had been exhibited operates a handle thereby shifting the shutters to conceal the positive number wheels and exhibit the negative simultaneously inserting a unit in the lowest decimal place of the totalizer. The correct total is then read from the negative number wheels.

In my present invention, the fact of the number wheels in the highest decimal place of the positive set changing from 0 to 9 will throw an auxiliary shutter over the positive number wheels. The totalizer then exhibits no number at all, since the positive wheels are closed by the auxiliary shutter, and the negative wheels are closed by the manually operated shutter. In case the operator should wish to read the negative total, it is necessary for her to first manipulate the handle. This will throw the manual shutter into a position to conceal the positive and exhibit the negative number wheels.

It is true that the positive number wheels are now concealed by two shutters, the auxiliary shutter before mentioned, and the manually operated one. However, that is immaterial to the concealing of the number

on the positive wheels, since the number is just as invisible when covered by two shutters as when covered by but one. The highest number wheel of the set adapted to exhibit 5 negative totals is also provided with an auxiliary shutter which operates in the same manner as the shutter for the positive set just described.

Summing up, assuming that the totalizer 10 exhibits a positive total, the subtraction of a greater number will cause the totalizer to exhibit no number at all until the handle is thrown to exhibit a negative total. The total then exhibited will be the correct one, 15 and will be the only number visible on the totalizer. Should a positive number greater than the exhibited negative total be afterward added, the negative total will become invisible, and in case this new total is to be 20 read the handle must again be shifted so as to display the positive total. It will be seen that I have in this improved algebraic totalizer a condition in which the totalizer will either exhibit the correct total or will 25 exhibit no number at all.

Having now described the theory of my invention I will go into the details of the construction and operation of a particular application of it. This may be best understood 30 by reference to the accompanying drawings of which—

Figure 1 is a side view of the totalizer on its supporting truck. Fig. 2 is a front view of the totalizer with the cover removed. 35 Fig. 3 is a vertical section on line 3—3 of Fig. 2. Fig. 4 is a perspective of the shutter and units adding mechanism. Some of the number wheels have been omitted in this last view for the sake of clearness.

40 The particular embodiment of my invention which I have herein described is designed to be used in connection with the Wahl calculating machine, which has been fully described in Patent 893,718 issued to 45 John C. Wahl, July 21st, 1908. Reference thereto will show a totalizer mounted on a typewriter carriage, a set of numeral keys, any of which serves to operate a master wheel 49 and a master dog 208; also that 50 the depressing of any numeral key results in the master wheel 49 and the dog 208 moving in the following sequence: (a) Dog 208 moves in a counter clockwise direction (Fig. 1), thus unlocking the chain of the totalizer 55 gears at the actuated gear. (b) The master wheel rotates an amount depending on the key actuated. (c) The dog returns to its original position. (d) The carriage escapes, bringing the totalizer wheel of the next 60 lower order into engagement with the master wheel. A reversing handle is also provided whereby the direction of motion of the master wheel consequent upon the actuating of any key will be determined and 65 thus numbers inserted in the machine either

additively or subtractively. Since the mechanism for producing these motions is very thoroughly described in the patent referred to, I shall not now enter into a further description of such mechanism, but shall premise that the actuating of a typewriter numeral key results in the master wheel, master dog and carriage moving in the sequence recited above. The master wheel numbered 49 and the master dog 208 in my present application correspond in position and function to the master wheel and master dog bearing the same numbers in the cited patent to Wahl referred to above.

Suitably supported by its side plates 10 and 11 is a totalizer constructed similarly to the totalizer of the above mentioned Wahl patent. This consists of a set of carrying gears 12 (Figs. 1 and 2) loosely mounted on a shaft 13 rigid between the plates 10 and 11 and which are adapted to coöperate *seriatim* with the master wheel 49 rotatably mounted in the framework, and a set of transfer gears 14 pivoted at 15 on a set of swinging arms 16. These arms are loosely mounted on the shafts 17 and 18, and their associated transfer gears 14 serve to connect the carrying wheels 12. Arms 16 have heels 19 adapted to be engaged *seriatim* by the master dog 208. The carrying gears 12 are provided with the usual carrying teeth which coöperate with the transfer gears 14 and thus transfer the tens at the proper time. The chain of gearing composed of the carrying gears 12 and the transfer gears 14 is normally locked. In order for the master wheel to operate on a carrying wheel at the middle of the chain the master dog 208 acts on a swinging arm 16, thereby raising the transfer gear 14 mounted thereon out of mesh with the carrying gears 12 to the right and left, thus unlocking the actuated carrying gear 12 from the next one to the right.

The totalizer is mounted on a truck 20 moving with the typewriter carriage. Numbers are inserted in the totalizer by the master wheel one digit at a time, beginning with the digit in the highest place and ending with the digit in the units place. During the insertion of a number the typewriter carriage escapes step by step to the left after the insertion of each digit, thus bringing successive carrying gears 12 into mesh with the carrying gear 49 and successive swinging arms 16 in a position to be acted on by the master dog 208.

The foregoing will be recognized as substantially the operation and structure of the totalizer in the above cited Wahl patent; the parts which are peculiar to my present invention are those which have to do with the indicating of positive and negative totals, and these parts will now be described. Rigidly supported between the side plates 10 and

11 is a shaft 28 on which is loosely mounted a set of idle gears 27, (Fig. 4), there being one gear 27 meshing with each carrying gear 12 of the totalizer. Meshing with each idle gear 27 are two gears 25 and 26 rotatably supported on shafts 21 and 22 rigid between the side plates. Rigid with the gears 25 and 26 are the positive figure bearing disks 23 and the negative figure bearing disks 24. 5 These have the figures from 0 to 9 inclusive on their periphery. There is a disk 23 and a disk 24 connected by means of an idler 26 to each carrying gear 12, and the gear connections are such that the disks 23 and 24 always revolve in the same direction. The 10 figures on these disks are arranged to progress in opposite directions and the totalizer is so assembled that when a 9 is on the reading line for the disk 23 a 0 is on the 15 reading line for the disk 24 and vice versa. 20 A suitable cover 29 for the totalizer is provided and this cover has two windows 30 and 31 through which the numbers exhibited by the disks 23 and 24 may be read. However, 25 since but one of these numbers is desired to be read at any particular time a shutter mechanism is provided for the superfluous number. This mechanism will now be described. Rotatably mounted on the shafts 21 30 and 22 are segmental gears 32 and 33. These serve as supports for the shutters 34 and 35, which extend over all the number disks on the respective shafts 21 and 22 and the shutters are riveted to the segmental gears 32 and 33. The shutters 34 and 35 are of suitable 35 width to register with the openings 30 and 31, and when either shutter is behind its corresponding opening the numbers on the number wheels associated with that opening 40 are, of course, concealed. The two segmental gears 32 and 33 are in mesh with an idle gear 36 rotatably mounted on the shaft 28. This idle gear in its turn is in mesh with a segmental gear 37 (best shown in Fig. 3), rotatably mounted on the shaft 13. It will be 45 readily seen that rotation of the segmental gear 37 will be transmitted through the idler 36 to the shutters and enable one or the other of the lines of figures to be viewed 50 through the windows 30 or 31, according to the position of the shutters. The segmental gear 37 is held in its position by a dog 38 rotatably mounted on the shaft 18 and held 55 in engagement with it by a spring 40. Referring now to Fig. 4, it will be seen that to the left of the highest number wheels of the totalizer are two auxiliary disks 55 and 56. 55 is on a shaft 21 carrying the positive number wheels and 56 is on the shaft 60 55 on which are mounted the negative number wheels. These auxiliary disks 55 and 56 are connected by a transfer gear 14 to the highest number wheel of the totalizer, and are so arranged that when the highest number wheel in the positive set, for instance, 65 changes from 0 to 9, the disk 55 will be moved so as to change the shutter 57 from the position shown in Fig. 4 into a position in line with the opening 30 of the cover 29. The disk 56 associated with the negative 70 number wheels is similarly constructed, and is so assembled that when the shutter 57 for the positive number wheels moves to be in line with the window 30 that a similar shutter 58 rigid with the disk 56 associated with the negative number wheels is out of line 75 with the opening 31. The purpose of this movement of the shutters has been thoroughly gone into in the beginning of this specification and need not be reviewed here. 80 Loosely mounted on the shaft 13 is a cam 41 which is rigidly connected to a handle 42 by studs 43 and 44, which extend through suitable slots 45 and 46 in the side plate 10. Rigid with the segmental gear 37 are two 85 studs 47 and 48, these being of sufficient length to engage the cam 41 when the latter is rotated. It will now be seen that movement of the handle 42 will be transmitted to the cam 41 and such motion by means of the engagement of the cam 41 with the stud 47, for instance, will serve to rotate the segmental gear 37, consequently changing the shutters so as to expose the alternative set of figures. Suitable studs 50 and 51 rigid in 90 the side plate 10 serve to limit the motion of the cam 41 in either direction. It will also be noticed that the cam 41 is provided with an extension 54 which engages the dog 38 and raises the dog from its engagement with the teeth of the segmental gear 37 during the 95 rotation of the latter. 100 It is well known that when a totalizer having a single set of reversible carrying mechanism is provided with two sets of figures from which both positive and negative totals may be read, the positive totals being 'read from one set of figures and the negative totals from the other, and further, that when these figures are paired in the relation of 9-0, 8-1, et cetera, an extra unit must be added to the set of figures to be read every time the totalizer passes through zero 110 in either direction. For instance, assuming that a positive total is exhibited by the totalizer and that a greater number than the total exhibited is subtracted, the set of wheels which had been exhibiting the positive total would now change to show a number preceded by 9's in the highest decimal 115 places, which number would be the correct arithmetical complement of the negative total, and a number would be exhibited on the set of figures from which the negative total is read, but the latter number, owing 120 to the wheels being paired in the relation of 9-0, would be one unit less than the correct amount. I have, therefore, provided mechanism operating coincidentally with the shifting of the shutter which will automatically 125 130

handle 42 will expose the correct total to be read. Consequently but one rule is necessary for operating this totalizer: Read the total exhibited or in case no total is shown, 5 shift the handle 42, and read the then exhibited total.

In my cited application Serial Number 751,032, filed February 27th, 1913, I have shown the shutters corresponding to shutters 34 and 35 of this application, having suitable legends inscribed on them directing the operator how to manipulate the machine to clear the totalizer; thus one shutter bears the legend Positive total. Erase by subtraction, 10 and the other shutter bears the legend Negative total. Erase by addition. Similarly, the auxiliary shutters 57 and 58, peculiar to my present invention, which are exposed to the view of the operator only in case it is necessary to manipulate the handle 42, may be inscribed with the legend Shift handle. I have not shown any of these legends on the drawings since their presence would simply tend to confuse the pictures 15 of the shutters themselves. However, the directions which I have given in this specification regarding these legends will be sufficient to enable one skilled in the art to paint them upon the shutters in their proper 20 places. It is to be noted that the legend Positive total. Erase by subtraction. is to be placed on the shutter numbered 35, the legend Negative total. Erase by addition. is to be placed on the shutter 34, and the legend Shift handle. is to be placed on both 25 the shutters 57 and 58.

It is to be noted that the Wahl machine with which this totalizer is assumed to be used is provided with a lever determining 40 the direction of rotation of the master wheel consequent upon the depression of any numeral key. By this means, numbers may be inserted into a totalizer either in addition or subtraction.

45 While I have described my invention as being used in a totalizer suitable for use with the Wahl machine, it is obvious that the invention is useful with any kind of a totalizer in which it is desirable to compute promiscuous positive and negative numbers.

Attention is directed to the simplicity of this device. While there have been algebraic totalizers proposed in the art in which the shifting of the shutters and the coincident adding of 1 in the units place of the totalizer has been done automatically as determined by the passage of the highest wheel through zero, yet any mechanism with which I am acquainted having this function is rather complicated. Considering that the number of times a total is read is small compared to the number of times an item is inserted into a totalizer, I am of the opinion that what the device herein shown lacks in the way of being automatic is more

than compensated for by its simplicity as compared to the automatic unit inserting mechanism.

Attention is directed to my cited co-pending application Serial Number 751,032 filed February 27th, 1913, in which I have claimed matters of invention herein disclosed but not claimed and I do not wish to claim herein any matters of invention disclosed in said cited application.

Many changes and modifications may be made in the precise structure herein shown and described without departing from the spirit of my invention, since

I claim:

1. In a calculating machine the combination of: a totalizer adapted to exhibit two numbers; a manually operated shutter co-operating with each of the numbers; and an automatically operated shutter co-operating with each of said numbers.

2. In a calculating machine the combination of: a totalizer adapted to exhibit two numbers; means to conceal one or the other of said numbers coincident with the passage of said totalizer through zero, and manually operated means to conceal one or the other of said numbers.

3. In a calculating machine the combination of: a set of carrying gears; a set of transfer gears; means for exhibiting a total; a shutter device moving coincidentally with the highest carrying gear of said set and adapted to conceal said exhibit total; and a manually operated shutter device also adapted to conceal said total.

4. In a calculating machine the combination of: a set of number wheels adapted to exhibit a positive total; a second set of number wheels adapted to exhibit a negative total; a shutter device co-operating with said number wheels; and mechanism to move the said shutter device coincident with the passage of either of said sets of number wheels through zero; and a manually operated shutter device also co-operating with said number wheels.

5. In a calculating machine the combination of: a totalizer adapted to exhibit either of two numbers; a designating device shiftable to designate either number; manual means to shift said designating device and simultaneously add a predetermined amount to the new number designated; and an automatic concealing device operated coincident with the passage of the totalizer through zero.

6. In a calculating machine the combination of: a totalizer adapted to exhibit either of two numbers; a master mechanism adapted to insert numbers in said totalizer digit by digit in either direction; a designating device shiftable to designate either number; manual means operating independently of said master mechanism to shift said design-

6
nating device and simultaneously add a pre-determined amount to the new number designated; and an automatically operated shutter device for concealing the exhibited number coincident with the passage of said totalizer through zero.

7. In a calculating machine the combination of: a totalizer embodying digit bearing members; means for actuating said members to register an amount thereon; means to add a digit thereto after an amount has been registered; shiftable means to designate certain digits on said digit bearing members; manual means operative on said digit adding means and said digit designating means whereby a digit may be added to said digit bearing members and the digit designating means simultaneously shifted at will; and a shutter device operated by said digit bearing members.

8. In a calculating machine the combination of: a totalizer adapted to exhibit two numbers; a manually operated designating device coöperating with each of the numbers; and an automatically operated shutter coöperating with each of said numbers.

9. In a calculating machine the combination of: a totalizer, including means to exhibit a total; means to conceal said total when said total is incorrect; and manual means to add an amount to said total and coincidentally exhibit said total.

10. In a calculating machine the combination of: a totalizer including means to exhibit a total; automatic means operating to conceal said total when said total is incorrect; and manual means to add an amount to said total and coincidentally exhibit said total.

40 11. In a calculating machine the combination of: a totalizer including means to exhibit a total; actuating mechanism adapted to insert numbers therein; means to conceal said total when said total passes through said total when said total passes through zero as a result of a number inserted by said actuating mechanism; and manual means to add an amount to said total and coincidentally exhibit said total.

12. In a calculating machine, the combination of a totalizer including exhibiting means to exhibit a total, means to prevent the exhibition of said total when said total is incorrect, and means to add a unit to said total and coincidentally exhibit it.

13. In a calculating machine, the combination of a totalizer adapted to exhibit either a positive or a negative total, a manually operated shutter coöperating with the exhibited total, and an automatically operated shutter coöperating with the exhibited total.

14. In a calculating machine, the combination of a totalizer having a set of numeral wheels and adapted to exhibit positive and negative totals, a manually operated shutter coöperating with said exhibited total, and a second shutter controlled by the highest wheel of said totalizer cooperating with said exhibited total.

15. In a calculating machine, the combination of a set of carrying gears, transfer mechanism connecting said gears, means for exhibiting a total, a shutter device moving coincidentally with the highest carrying gear of said set and adapted to conceal said exhibited total, and a manually operated shutter device also adapted to conceal said total.

16. In a calculating machine, the combination of a set of carrying gears, transfer mechanism connecting said gears, means for exhibiting a total, a shutter device moving co-incidentally with the highest carrying gear of said set and adapted to conceal said exhibited total, a manually operated shutter device also adapted to conceal said total, mechanism to insert a unit in the lowest place of said totalizer, and an operating means common to both said manual shutter and said unit inserting device.

In witness whereof, I have hereunto subscribed my name in the presence of two witnesses.

ARTHUR F. POOLE.

Witnesses:

R. GEO. C. BOA,
JOHN C. WAHL.
